US00D921608S

(12) **United States Design Patent** (10) Patent No.: **US D921,608 S**
(45) Date of Patent: **** Jun. 8, 2021**

(54) **HEADPHONES**

(71) Applicant: **Apple Inc.**, Cupertino, CA (US)

(72) Inventors: **Shota Aoyagi**, San Francisco, CA (US);
Robert Boyd, Los Angeles, CA (US);
Robert Brunner, Glen Ellen, CA (US);
Monica Fernandez, Reseda, CA (US);
Christopher Kuh, San Francisco, CA (US);
Christopher J. Stringer, Woodside, CA (US)

(73) Assignee: **Apple Inc.**, Cupertino, CA (US)

(**) Term: **15 Years**

(21) Appl. No.: **29/720,426**

(22) Filed: **Jan. 13, 2020**

Related U.S. Application Data

(63) Continuation of application No. 29/667,339, filed on Oct. 19, 2018, now Pat. No. Des. 874,429, which is a continuation of application No. 29/622,980, filed on Oct. 20, 2017, now Pat. No. Des. 831,610, application No. 29/720,426, filed on Jan. 13, 2020, which is a continuation of application No. 29/667,334, filed on Oct. 19, 2018, now Pat. No. Des. 873,791, which is a continuation of application No. 29/622,980,

(57) **CLAIM**

The ornamental design for headphones, as shown and described.

DESCRIPTION

FIG. 1 is a front perspective view of headphones showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the figures show portions of the headphones that form no part of the claimed design.

The dot-dash lines in the figures show boundaries that form no part of the claimed design.

1 Claim, 5 Drawing Sheets
